UNITED STATES PATENT OFFICE.

JAMES L. CRAIG AND ALEXANDER BLYTH CRAIG, OF SAN FRANCISCO, CALIFORNIA.

SCREW HOLDER AND DRIVER.

Application filed February 11, 1925. Serial No. 8,380.

To all whom it may concern:

Be it known that we, JAMES L. CRAIG and ALEXANDER BLYTH CRAIG, citizens of the United States, residing at city and county of San Francisco, and State of California, have invented new and useful Improvements in Screw Holders and Drivers, of which the following is a specification.

This invention relates to tools and particularly to a new and improved screw driver having means cooperating therewith for securely holding a screw in straight driving position while the same is being driven. We are aware that various devices have been provided for performing this function and it is the primary object of our invention to provide an improved device of this type and for this purpose which is comparatively simple in construction and strong and efficient in operation.

In accordance with our invention, we support a sleeve for axial movement on the shank of an ordinary screw driver near the bit end. This sleeve pivotally carries a pair of screw engaging jaws on the lower end thereof. In the lowermost position of the sleeve the screw engaging portions of the jaws are below the bit while in the upper position such portions are above the bit and out of interfering position therewith. Means is carried by the sleeve for moving the jaws into and out of screw engaging position. It is a further object of our invention to provide a very convenient and efficiently operating device of this character.

With the above and other objects in view, our invention consists in the features of construction and operation set forth in the following specification and illustrated in the accompanying drawing. In such drawing annexed hereto and forming a part of this specification we have illustrated one specific embodiment of our invention, but it will be understood that the invention can be otherwise embodied and that the drawing is not to be construed as defining or limiting the scope of the invention, the claims appended to this specification being relied upon for that purpose.

50 Referring to the figures of the drawing:

Fig. 1 is an elevation of a screw driver having our improved device mounted thereon, the device being illustrated in longitudinal section.

55 Fig. 2 is a like view showing the parts in another position.

Fig. 3 is an elevation of the device showing the parts in another position.

Fig. 4 is a bottom plan view of the device.

Fig. 5 is a cross section taken on line 60 V—V of Fig. 1.

Fig. 6 is a detail view of one of the screw holding jaws.

Referring more specifically to the drawing by reference characters, 1 indicates the 65 shank of a screw driver having a handle 2 on one end and having its other end formed into a driving bit 3. Our improved screw holding device which cooperates therewith is supported on a sleeve 4 adapted to be secured to the shank by a pin 5.

A second sleeve 6 is mounted on the sleeve 4 and normally rests against a shoulder 7 on the lower end thereof. This sleeve 6 is 75 slideable axially on the sleeve 4 to two positions and is held in such positions by a spring pressed ball 8 engaging in either of two annular grooves 9 and 10 in the sleeve 4.

Upward movement of the sleeve 6 is limited by a nut 11 on the sleeve 4 and downward movement thereof is limited by the shoulder 7.

Pivoted to the lower end of the sleeve 6 at 12 are two screw holding jaws 13. A pair of screw engaging and holding elements 14 are swiveled to the lower ends of the jaws, this swivel connection permitting the elements to automatically adjust themselves to the proper engagement of different sized screws. A jaw operating member 15 is 90 slidably and rotatably mounted on the sleeve 6 and a lower annular ring portion 16 thereof surrounds the jaws 13. Movement of the member 15 downwardly to the position shown in Fig. 1 is adapted to engage the 95 jaws with a screw 17 to be driven, while movement thereof upwardly to the position shown in Fig. 2 is adapted to engage the ring portion 16 with the upper ends 18 of the jaws and withdraw the elements 14 from 100 the screw.

The operation of our improved device when mounted on a screw driver, as illustrated, is substantially as follows: The parts are moved to the position shown in 105 Fig. 2 and a screw 17 is placed in the position illustrated. The member 15 is then moved downwardly to engage the portion 16 with the jaws to move and hold the elements 14 thereof firmly engaged with the screw. 110 In this position, the screw is firmly held and the bit 3 is in engagement therewith. The

screw, being thus supported, the same can be driven straight without any of the difficulties usually encountered. To drive the screw entirely home the operator lifts the member 15 upward to the position illustrated in Fig. 3. The first movement thereof engages the ends 18 of the jaws and swings the elements 14 away from the screw and the final movement thereof lifts the sleeve 6 and jaws to a position above the bit. The parts are held in this position by the ball 8 engaging in the groove 10.

It is believed that the construction, operation and the several advantages of our invention will be clear without further description herein. Obviously, an operator can manipulate the screw driver with one hand on the handle 2 and use the other hand to operate the member 15.

Having thus described our invention, what we claim and desire to secure by Letters Patent is:

1. A screw driver comprising a shank having a driving bit on one end thereof, a sleeve carried by the shank near the bit, a pair of jaws pivotally carried by the sleeve, a pair of screw engaging and holding elements swivelly carried on the bit ends of the jaws, and means carried by the sleeve and cooperating with jaws for pivoting the jaws in one direction to engage and hold a screw in the said elements and in the opposite direction to disengage the elements from the screw, the swivel mounting of the screw holding elements permitting the elements to automatically adjust themselves to the proper engagement of different sized screws.

2. A screw driver comprising a shank having a driving bit on one end thereof, a sleeve carried by the shank near the bit, a pair of jaws pivotally carried by the sleeve and having means on the bit end thereof for engaging a screw, and means carried by the sleeve and cooperating with the bit ends of the jaws to engage the same with a screw when the said means is moved axially on the sleeve in one direction and cooperating with the other ends of the jaws at the other side of the pivots to disengage the jaws from the screw when moved axially on the sleeve in the opposite direction.

3. A screw driver comprising a shank having a driving bit on one end thereof, a sleeve carried by the shank near the bit, a pair of jaws pivotally carried by the sleeve and having means on the bit end thereof for engaging a screw, means carried by the sleeve

and cooperating with the jaws for pivoting the jaws in one direction to engage and hold a screw engaged by the bit and in the opposite direction to disengage the jaws from the screw, the sleeve being movable axially away from the bit to draw the jaws from interference with the operation of the bit, and means for holding the sleeve in such position.

4. A screw driver comprising a shank having a driving bit on one end thereof, a sleeve carried by the shank near the bit, a pair of jaws pivotally carried by the sleeve and having means on the bit end thereof for engaging a screw, and an element carried by and slidable axially on the sleeve and having means cooperating with the outer surfaces of the jaws whereby movement of the element axially on the sleeve in one direction will force the jaws into engagement with a screw engaged by the bit.

5. A screw driver comprising a shank having a driving bit on one end thereof, a sleeve carried by the shank near the bit, a pair of jaws pivotally carried by the sleeve and having means on the bit end thereof for engaging a screw, and an element carried by the sleeve and having an annular ring portion surrounding the jaws whereby movement of the element axially in one direction will engage the ring portion with the jaws and force the jaws into engagement with a screw engaged by the bit, the element being rotatable relative to the sleeve and jaws without affecting its jaw holding function.

6. A screw holding device adapted to cooperate with a screw driver having a shank with a driving bit on one end thereof, a sleeve adapted to be secured on the shank near the bit end thereof, a second sleeve slidable axially to two positions on the first sleeve, a pair of jaws pivotally carried by the second sleeve and having means on the bit ends thereof for engaging a screw to be driven by the bit, the second sleeve in one axial position holding the screw-engaging portions of the jaws below the bit and in the other position holding the same above the bit, and means slidable axially on the second sleeve and cooperating with the jaws, movement thereof toward the bit being adapted to close the jaws and movement thereof in the opposite direction being adapted to open the jaws.

JAMES L. CRAIG.
ALEXANDER BLYTH CRAIG.
